CLAIM

I claim the ornamental design for a potted plant hidden camera, as shown and described.

DESCRIPTION

FIG. 1 is a front plan view according to the present invention;

FIG. 2 is a rear plan view thereof;

FIG. 3 is a bottom plan view thereof;

FIG. 4 is a top side view thereof; and,

FIG. 5 is a left side view thereof.

The broken lines and the portions immediately adjacent to the broken lines shown in the drawings represent portions of the potted plant hidden camera that form no part of the claimed design.
